UNITED STATES PATENT OFFICE.

RICHARD B. HUNTER, OF MILWAUKEE, WISCONSIN, ASSIGNEE TO THE CUTLER-HAMMER MFG. CO., OF MILWAUKEE, WISCONSIN, A CORPORATION OF WISCONSIN.

DRUM CONTROLLER.

Application filed July 19, 1920. Serial No. 397,374.

To all whom it may concern:

Be it known that I, RICHARD B. HUNTER, a citizen of the United States, residing at Milwaukee, in the county of Milwaukee and 5 State of Wisconsin, have invented new and useful Improvements in Drum Controllers, of which the following is a full, clear, concise, and exact description, reference being had to the accompanying drawing, forming 10 a part of this specification.

This invention relates to drum controllers and more particularly to controllers adapted to effect joint control including series parallel commutation of a plurality of electric 15 motors.

An object of the invention is that of providing a simplified controller for the foregoing purposes comprising a minimum number of parts compactly and conveniently 20 arranged.

Other objects and advantages will herein-after appear.

The accompanying drawing illustrates diagrammatically certain of the embodiments 25 which the invention may assume in practice and the same will now be described, it being understood that the invention is capable of embodiment in various modified forms falling within the scope of the appended claims.

30 In the drawing, Fig. 1 illustrates a preferred embodiment of the invention; while,

Fig. 2 illustrates a slightly modified form thereof.

35 Referring to Fig. 1 of the drawing, the same illustrates a drum controller adapted to effect acceleration control including series parallel commutation of a pair of electric motors M^1 , M^2 , the latter to be supplied with 40 current from lines L^1 , L^2 , and being provided with steps of starting resistance r^1 to r^4 .

More particularly the drum controller 45 comprises a set of eight stationary contacts designated as 10 to 17, and a co-operating rotatable drum carrying contact segments designated by the same reference numerals as their corresponding fixed contacts but supplemented by letters *a* or *b*. The segments are divided into three electrically independent groups whereas the segments of each group are electrically connected.

50 As illustrated, the controller is adapted to effect eight distinct operating points indicated by lines *a*, *b*, *c*, *d*, *x*, *e*, *f*, *g* of which *a*

to *g* indicate acceleration or resistance variation points while *x* indicates the transition point from series to parallel or vice versa.

In position *a* of the controller the stationary contacts 12 and 15 are engaged respectively by their co-operating segments 12^a and 15^a whereby the motors are connected across the supply lines in series with one another through resistances r^1 to r^4 , the circuit connections being obvious. 60

In position *b* resistance r^1 is excluded through engagement of segment 10^a with its contact 10. In position *c* segment 14^a is in engagement with its associated stationary contact 14 whereby resistances r^2 and r^3 are 70 both excluded, whereas when in position *d*, segment 13^a engages contact 13 thereby connecting the motors in series directly across the supply lines.

Upon movement of the controller to position *x*, the connections last described are maintained whereas engagement of the respective segments 11^b, 12^b, 15^b and 16^b with their co-operating fixed contacts serves additionally to connect the motors across the line 80 in parallel with one another, resistances r^1 and r^4 being included in the circuit of motor M^1 and resistances r^2 and r^3 being included in the circuit of motor M^2 . 75

Movement of the controller to position *e* 85 serves to interrupt the series connection between the motors, the parallel connections thereof being unaffected.

Movement of the controller to position *f* serves to exclude resistance r^1 from the circuit of motor M^1 and similarly to exclude 90 resistance r^2 from the circuit of the motor M^2 ; while movement of the controller to position *g* serves to connect said motors directly across the supply lines in parallel 95 relation.

Obviously by the foregoing arrangement the motor circuits when connected in parallel are maintained of substantially equal resistance, similar resistance variations being 100 simultaneously effected in both.

Where such equality of the resistance value in the two circuits is not essential and where it is expedient to increase the number of operative positions of the controller and the number of segments thereof, it is possible to effect a material increase in the number of acceleration points without any increase in the number of fixed contacts or resistance steps. 105 110

Such an arrangement is illustrated in Fig. 2 of the drawing wherein the arrangement of the fixed parts of the controller is identical with that aforescribed. In this instance, however, the number of operating points of the drum has been increased to eleven, the number of segments being increased by addition of segment 17^a.

The co-operation of the various controller parts and the connections effected thereby are identical with those aforescribed except that the angular positions and ranges of certain segments have been adjusted to provide for exclusion of the resistance steps progressively in each instance, thus providing for starting and acceleration of the motors in eleven progressive stages or operating points of the controller inclusive of the transition stage, whereas the formerly described construction provided but eight such stages.

Since in series-parallel controllers as heretofore constructed ten stationary contacts and a correspondingly increased number of co-operating parts were required to provide the number of operating points effected by the construction of Fig. 1, it is obvious that each of the aforescribed constructions is adapted to effect a material conservation in the number of parts and in space requirements.

What I claim as new and desire to secure by Letters Patent is:

1. A series parallel drum controller comprising a plurality of contacts and a plurality of electrically independent sets of segments, certain of said sets of segments being co-operable with certain of said contacts to effect all the parallel circuit connections provided by the controller and other of said sets of segments being co-operable with certain of said contacts to effect all the series circuit connections, the number of said contacts being not greater than the number of operative positions of the controller.

2. A series parallel drum controller comprising a plurality of contacts and a plurality of segments, the latter being arranged in three electrically independent groups, two of said groups of segments being jointly co-operable with certain of said contacts to effect all the parallel circuit connections provided by the controller and the third set of segments being co-operable with certain of said contacts to effect all the series circuit connections, certain of said segments being arranged to maintain continuity of circuit during series parallel commutation, the number of said contacts being not greater than the number of operative positions of the controller.

3. A drum controller adapted to effect control including resistance variation and series parallel commutation of a plurality of circuits, comprising a plurality of drum seg-

ments and a plurality of contacts to be engaged thereby, the number of said contacts being not greater than the number of operating points of the controller and being not more than four greater than the number 70 of resistance sections to be commutated.

4. A controller for a plurality of motors comprising a plurality of contacts and a plurality of drum segments co-operable therewith to provide a number of operating 75 points including resistance variation and series parallel commutation points, said contacts and segments being co-ordinated to maintain continuity of circuit during series parallel commutation and the number of 80 said contacts being not greater than the number of said operating points and being not greater than half the number of resistance sections to be commutated.

5. A controller for a plurality of motors 85 comprising steps of series resistance for the motors, a plurality of contacts and a plurality of drum segments co-operable therewith to provide a number of operating points including resistance varying and series parallel 90 commutation points, the number of said contacts being not greater than the number of said operating points and being not greater than twice the number of said resistance steps.

6. A controller for a plurality of motors comprising steps of series resistance for the motors, a plurality of contacts and a plurality of drum segments co-operable therewith to provide a number of operating points including resistance varying and series parallel 100 commutation points, the number of said contacts being twice the number of said resistance steps and being less than the number of said operating points.

7. A controller for effecting resistance variation and series parallel commutation of the circuits of two motors, comprising four steps of series resistance for the motors, eight contacts and a number of drum segments co-operable therewith to provide eleven operating points inclusive of resistance variation and transition points, said contacts and segments being arranged to maintain continuity of circuit of the motors 110 during series parallel commutation.

8. The combination with a supply circuit L^1 , L^2 , and translating devices M^1 , M^2 , respectively connected to lines L^1 , L^2 , of resistance, including sections r^1 to r^4 , and a 120 drum controller comprising contacts 10 to 17 and three sets of co-operating segments, one set including segments 10^a, 12^a, 13^a, 14^a and 15^a, another set including segments 10^b, 11^b, 12^b and 13^b and a third set including 125 segments 14^b, 15^b, 16^b and 17^b substantially as shown, contacts 11 and 14 being respectively connected to opposite terminals of translating device M^2 , contacts 13 to 16 being respectively connected to opposite ter- 130

minals of translating device M^1 , contacts 10 and 12 being connected through resistance r^1 , contacts 10 and 13 being connected through resistance r^4 , contacts 14 and 17 being connected through resistance r^3 and contacts 15 and 17 being connected through resistance r^2 , whereby said controller may be operated to selectively establish series or parallel connections for said translating devices inclusive and exclusive of said resistance.

In witness whereof, I have hereunto subscribed my name.

RICHARD B. HUNTER.
